UNITED STATES PATENT OFFICE.

OLE EDWARD WICK AND GEORGE C. WICK, OF CHICAGO, ILLINOIS.

ORGAN.

SPECIFICATION forming part of Letters Patent No. 536,247, dated March 26, 1895.

Application filed September 20, 1894. Serial No. 523,567. (No model.)

To all whom it may concern:

Be it known that we, OLE EDWARD WICK and GEORGE C. WICK, of Chicago, in the county of Cook and State of Illinois, have invented certain new and useful Improvements in Organs; and we do hereby declare that the following is a full, clear, and exact description thereof, reference being had to the accompanying drawings, and to the letters of reference marked thereon, which form a part of this specification.

This invention relates to improvements in reed organs, and has reference more particularly to the construction of the casing whereby the same is adapted to serve both as an organ casing and also as a desk provided with the usual accessories. Certain features of the invention are, however, applicable to organ cases alone.

The invention consists in the matters hereinafter described and more particularly pointed out in the appended claims, and the same will be more readily understood by reference to the accompanying drawings, in which—

Figure 1 is a central transverse vertical sectional view of an organ embodying our invention. Fig. 2 is a horizontal section taken on the line 2—2 of Fig. 1, and looking downwardly, parts being broken away to expose the mechanism beneath. Fig. 3 is a fragmentary view similar to that of Fig. 1, but showing the sliding desk top drawn out. Fig. 4 is an inside elevation of the vertically movable slide which closes the space beneath the sliding desk top and in front of the bank of keys, showing also its actuating arms and springs. Fig. 5 is a fragmentary view similar to that of Fig. 1, but showing the desk top drawn out and the pigeon-hole screen retracted or folded back within the hood. Fig. 6 is a view similar to that of Fig. 2, showing the sliding desk top drawn out, part of the latter being broken away to expose the arrangement of the locking mechanism by which it is held from accidental retraction. Fig. 7 is a central vertical section of the lower part of the organ, showing the positions assumed by the pedals and pedal support when folded inward. Fig. 8 is a horizontal section, showing the pedals and operating connections in plan view.

As shown in said drawings, the organ casing consists of the usual main lower part A within

which the bellows and pedal mechanism are arranged, a central portion A' separated from the former by a base board a, within which are arranged the wind chest a' and reed mechanism, and an upper portion or hood A² between which and the central portion is a sliding partition or sliding top B adapted to be drawn out to form a writing surface. The main portion of the space within the hood A² is herein shown as occupied by a casing B' containing pigeon holes and drawers such as are commonly present in roll top or curtain desks. Said hood also contains a curtain or flexible cover A³ adapted to be drawn out and down over the desk B, and to thereby close the front of the hood A² and cover the writing surface, in a familiar manner. In the hood A² at either side of the casing B' will preferably be located the organ stops, in the manner set forth in a prior patent, No. 385,031 dated June 26, 1888.

In the construction herein shown the main lower section A, upper section or hood A², and one end of the central section A' are formed by means of vertical side or end walls a² a², back wall portions a³ a³, and a horizontal top board a⁴. The other inclosing side or end wall a⁵ and the rear wall a⁶ of the central portion A' of the casing are made in the form of doors hinged at their lower edges so, as to drop down outwardly, and conveniently held closed by turn-buttons; thus providing ready access to this part of the organ. A removable board a⁷ extending up from a permanent front bar a¹³ to the level of the bottom of the bank of keys forms the front wall of the central portion A'. In the lower main part A, between and parallel with the exterior end walls a² a² are two vertical partitions a⁸ a⁸, forming, in conjunction with cross partitions or backs a⁹ a⁹, at either side of the casing, compartments A⁴ A⁴, which may be divided into spaces for books or a series of drawers or pigeon holes, or may be otherwise utilized as common in office desks. The exterior of these side spaces will preferably be finished alike so as to give when closed a uniform appearance to both sides of the casing. Extending between the partitions a⁸ a⁸ and parallel with the rear wall a⁸ is placed a vertical partition a¹⁰ which forms a shallow recess in the front of the casing. Through the lower part of said parti-

tion is formed the pedal opening a^{11} . Back of the compartments A^4 A^4 and partitions a^{10} is the bellows chamber. The partitions a^9 a^9 and a^{10} extend up to the base board a , which 5 extends the full length of the organ and entirely separates the lower part A from the central part A'. The keys C of the organ are located in the upper forward portion of the chamber A' and are covered when the organ 10 is not in use by the top B, which latter is made to slide horizontally so that it may be either drawn forward over the keys and form a writing table or thrust backwardly to uncover the keys when it is desired to use the organ.

15 The ends of the sliding top B are provided with tongues which engage corresponding grooves or ways b b formed in cleats b' secured against the end walls of the casing.

For the purpose of closing the space at the 20 front of the keys when the top B is drawn forward and the organ is not in use, a vertically sliding panel D is provided which overlaps at its lower edge the front wall a^7 and is arranged to rest normally within a rabbet 25 formed in the said front wall, as clearly seen in Figs. 1 to 4. Said sliding panel is provided with depending guide pins d d which rest within and slide through bearings or sockets d' d' secured upon the inner face of the panel 30 a^7 . At its upper edge said panel D is provided with a cap piece d^2 which is wider than the upper edge of the panel and projects over the outer wall a^7 thus forming a finish for the same. The panel D is somewhat thicker than 35 the width of the rabbets within which it rests, thus forming at its lower edge an overhanging ledge d^3 which is engaged by lifting arms d^4 d^4 pivotally mounted at the rear or inner face of the board a^7 , as clearly shown in Fig. 40 4. Means for oscillating the arms d^4 upon the pivots in a manner to cause their rounded upper ends to act upwardly on the ledge d^3 and thereby lift the panel D, are provided as follows:

45 Referring to Fig. 2, E is a bent lever pivotally mounted to swing in a horizontal plane, upon a cross piece a^{12} secured against the inner rear wall of the casing. Said lever is so arranged as to lie immediately beneath the 50 sliding desk top B, and the latter is provided with a roller b^2 depending from its under side at the rear edge in such position as to engage the lever E at its rear side, said roller resting between the pivot and the angle of the lever 55 when the desk top is at the backward limit of its movement. When in this position, as shown in said Fig. 2, the bent end of the lever extends diagonally across the path of the roller b^2 , so that as the latter is carried forward said lever is swung forward upon its 60 pivot e until the bent end assumes a position parallel with the path of movement of the said roller, after which the roller will, in its further outward movement, merely hold the lever stationary. In order that the roller in 65 thus actuating the lever may also support it in a horizontal plane, the lever is provided

with an undercut rabbet e' which is engaged by the edge of the roller b^2 , as indicated in dotted lines, Fig. 2.

E' is a rod connected at one end with the lever E near the angle thereof, and at its other end with a short change motion lever E^2 carried by a bracket e^2 also secured on the cross piece a^{12} . From the other end of the lever E^2 75 a rod E^3 extends to and engages an arm e^3 on a third rod or rock-shaft E^4 mounted horizontally at right angles to the rod E^3 on bearings e^4 e^4 secured to the end wall of the organ casing. The end of the rock-shaft E^4 opposite that attached to the rod E^3 is also provided with an arm e^5 standing at right angles to the shaft and in approximately the same plane with the lifting arms d^4 d^4 of the panel. The arms e^3 e^5 of the rock-shaft E^4 are arranged to stand in approximately the same 85 radial plane, and the length of the connecting rod E^3 is such as to hold said arms, when thrown outwardly by the lever E^2 , to its farthest limit, nearly in a vertical position, and 90 when retracted to oscillate the rock-shaft through approximately one eighth of a revolution. The end e^5 of said rock-shaft is connected with the lifting arms d^4 d^4 by means of a connecting rod E^5 , as clearly shown in 95 Fig. 4. As thus arranged the drawing forward of the desk top B causes the roller b^2 to act on the lever E, and, through the connections described, raises the panel D and closes the space in front of the keys.

In order that the panel D may be drawn down certainly and independently of its own gravity when the desk top is thrust inward, S-shaped wire springs d^5 d^5 are secured on the inner face of the casing and arranged to 105 act on studs d^6 d^6 secured in the panel in such manner as to depress the same. It is to be noted in this connection that the panel D is entirely disconnected from its lifting mechanism and may be lifted out by simply disengaging the ends of the springs from the 110 studs d^6 .

When used as a desk it is, of course, desirable that the pedals of the organ be in some manner disposed of so that they shall 115 be out of the way and out of view, and to this end means are herein shown whereby the pedals are folded within the casing and their supporting base arranged to form a closure for the pedal opening in the casing. 120 This may, of course, be effected in various ways, either by separate independent mechanism adapted therefor, or they may be arranged to be simply folded in by hand, but as herein shown means are provided whereby 125 the change in arrangement is effected simultaneously with and by the drawing out of the desk top. Said means are as follows:

F is a rock-shaft mounted vertically in bearings in one end of the casing and provided with two radially projecting arms, one at the upper end extending in the same horizontal plane with the lever E, shown in full lines at f (Fig. 2), and the other at the lower

end of the rock-shaft and arranged at a different radial angle, as shown in dotted lines at f' .

F' is a rod connecting the upper arm f with the free end of the lever E . The lower arm f' is connected with a horizontally arranged lever F^2 pivotally mounted on the bottom of the casing by means of a short connecting rod F^3 . The lever F^2 reaches from the rod F^3 to a point immediately in the rear of the central portion of the pedal support (all as shown in dotted lines in Fig. 2) and is there connected with the lower end of depending pendulum lever F^4 by means of a connecting link 10 or rod F^5 . The lever F^4 is adapted to swing in a vertical plane in a direction from the front to the rear of the casing.

G is the pedal support or base pivoted at one edge in the lower side of the pedal opening a^{11} so as to fold upwardly and form a closure for said opening.

F^6 is a short link or rod pivotally connected at one end with the central upper surface of the pedal support or base G beneath the ped- 25 als G' and engaging at its other end the pendulum lever F^4 at a point a short distance above its lower end. The pedals G' are hinged at their lower edges to the support G and supported in an inclined position by the bel- 30 lows straps $g\ g$ attached to their rear edges and trained from thence over guide pulleys g' to the upper ends of the bellows H , in the usual manner. Thus connected and arranged the swinging of the lever E caused by 35 pulling out the desk top B acts on the rock-shaft F , which in turn acts on the lever F^2 causing the latter to draw the pendulum lever back toward the rear of the casing. The movement of the pendulum lever draws up 40 the pivoted base G carrying the pedals G' and closes the opening in the casing, the various parts assuming the positions indicated in dotted lines in Fig. 1. The outer or under side of the base G will, of course, be finished 45 to present a uniform appearance with the exterior of the casing.

It will be obvious from the foregoing that it is desirable that the desk top when drawn out should be secured against accidental closing, and for this purpose catches or locks are provided as follows:

I are small bell crank levers pivoted at i to the under face of the desk top B . The longer arms of the bell cranks are provided 55 with pivotally attached bolts or catches $i\ i$ arranged to extend outwardly through guide apertures formed through marginal cleats secured to the under side of the desk top B .

$I'\ I'$ are springs also secured to the under 60 face of the desk top and acting on said longer arms in a manner to throw the catches i' outwardly into recesses $i^2\ i^2$ in the casing when the desk top is fully drawn out, as indicated in Fig. 6. In order to withdraw the bolts $i\ i'$ 65 from said recesses rods $I^2\ I^2$ are connected with the shorter arms of said bell cranks and extend forwardly to points near the front mar-

gin of the desk top, at which points they are provided with upturned ends which extend through slot apertures $b^3\ b^3$ and are provided 70 with small T-heads by which they may be conveniently manipulated. For neatness of finish the T-heads are let into circular de- 75 pressions so as not to rise above the main sur-
face of the desk top.

As it is desirable that a screen or cover be provided for the front of the pigeon holes, drawers, &c., which occupy the principal space within the hood A^2 , especially when ar- 80 ranged for use as an organ, improved devices for this purpose are herein shown. The cas- 85 ing B' arranged within the hood and contain- 90 ing the pigeon holes, &c., is generally rectangular in form and is slightly less in length than the interior of the hood. At each end of the casing at its lower central margin is pivoted a lever J adapted to oscillate in a ver- 95 tical plane parallel with the end of the casing B' and of proper length to extend diagonally upward to either upper corner of the casing. The levers $J\ J$ are connected at their upper ends by means of a cross bar J' extending the length of the casing B' and pivotally hung so as to rest upon the upper surface of the cas- 95 ing when the levers are thrown to either their backward or forward limits of movement.

J^2 is a screen hinged at one edge to the cross bar J' in such manner that when said bar is in its backward position, as shown in Fig. 5, it will rest flatly upon the top of the casing 100 B' , or when the bar is in its forward position, to hang vertically in front of the casing B' .

From the above it will be obvious that when the curtain is thrown back the screen may be placed in position to close or cover the front 105 of the pigeon holes by simply drawing it for- 110 ward and allowing it to drop down, or re- 115 placed in the position shown by simply lift- 120 ing it out into a horizontal position and push- 125 ing it back, when the bar connected with the levers will be carried back in an arc, thus holding the screen bodily up free from the top of the casing in its backward movement and preventing rubbing of the screen on the casing.

From the above description it will be obvi- 130 ous that a casing constructed in accordance with our invention possesses many valuable features of improvement. Among these may be mentioned that the casing when closed up and with the pedal support in its folded po- 135 sition forms an almost perfectly close inclo- 140 sure, thereby preventing mice or other vermin from gaining access to the interior of the organ. It will also be apparent that many of the fea- 145 tures are independent and capable of embodiment separately as well as in the manner herein shown. We do not, therefore, desire to be limited to the particular arrangement herein shown nor to precise details of construction, but, on the contrary, desire to claim broadly the various novel features specified.

We claim as our invention—

1. The combination with an organ casing,

of a sliding top, a vertically movable panel for closing the space in front of the keys, a folding pedal support, and means connecting said sliding top with said sliding panel and 5 folding pedal support, whereby the latter are actuated from the former, substantially as described.

2. The combination with an organ casing having a sliding top, of a vertically sliding 10 panel for closing the space in front of the keys, a folding pedal support, and means for actuating said movable panel and folding pedal support, comprising a lever pivoted at the rear of the casing to swing in a horizontal 15 plane, a projection on the sliding top engaging said lever, operative connections between said lever and the sliding panel, and operative connections between the said lever and the folding pedal support, substantially as described. 20

3. The combination with an organ casing, of a sliding top, a folding pedal support, and means for actuating the pedal support from the sliding top, comprising a vertical shaft, 25 which is turned by the movement of the top, a rigid arm on the lower end of the shaft, and a swinging lever movable from front to rear of the casing and connected at its lower end with the said arm and also with said folding 30 pedal support, substantially as described.

4. The combination with an organ casing, of a sliding top, a pedal support and means for actuating the pedal support from the sliding top, comprising a vertical shaft, a rigid 35 arm at the lower end of the shaft, a horizontal lever mounted on the bottom of the casing and connected with the said arm of the shaft, a swinging arm pivoted to swing from front to rear of the casing, and rods connecting said 40 swinging arm to the said lever and to the folding pedal support, substantially as described.

5. The combination with an organ casing, of a sliding top, a pedal support and means for actuating the pedal support from the sliding 45 top, comprising a horizontal lever mounted on the bottom of the casing, a swinging arm pivoted to swing from front to rear of the casing, and connections between said swinging arm and the pedal support and between the horizontal lever and said sliding top, substantially 50 as described.

6. The combination with an organ casing, of a sliding top, a pedal support and means for actuating the pedal support from the sliding 55 top, comprising a swinging arm pivoted to swing from front to rear of the casing, and connections between said swinging lever and pedal support and swinging lever and sliding top, substantially as described.

60 7. The combination with the keys of an organ, of a rigid horizontally sliding top located over and adapted to cover the keys and to form a desk top when drawn forward, a separate vertically sliding panel at the front of the 65 case, adapted to be lifted for closing the space in front of the keys, and means for actuating said panel by the movement of the sliding

top, comprising a lever pivoted to the rear part of the casing and adapted to swing in a horizontal plane, a roller on the sliding top 70 acting on said lever, a rock-shaft on one side of the casing, and operative connections between said rock-shaft and said lever and between the rock-shaft and the sliding panel, substantially as described. 75

8. The combination with the keys of an organ, of a rigid horizontally sliding top located over and adapted to cover the keys and to form a desk top when drawn forward, a separate vertically sliding panel at the front of the case, 80 adapted to be lifted for closing the space in front of the keys, and means for actuating said panel by the movement of the sliding top, comprising a lever pivoted at the rear part of the casing and adapted to swing in a horizontal plane, a roller on the sliding top 85 acting on said lever, a rock-shaft on one side of the casing, and connections between said rock-shaft and lever embracing an intermediate lever and two connecting rods, substantially as described. 90

9. The combination with the keys of an organ, of a rigid horizontally sliding top located over and adapted to cover the keys and to form a desk when drawn forward, a separate vertically sliding panel at the front of the case, 95 adapted to be lifted for closing the space in front of the keys, and means for actuating said panel by the movement of the sliding top, comprising a lever pivoted at the rear part of the casing and adapted to swing in a horizontal plane, a roller on the sliding top 100 acting on said lever, a rock-shaft on one side of the casing, and connections between said rock-shaft and panel, comprising arms swinging in vertical planes and acting on the panel to lift the same, and rods connecting said arms with the rock-shaft, substantially as described. 105

10. The combination with an organ casing, a sliding top and a vertically sliding front panel for closing the space in front of the keys, of springs applied to depress the panel, arms pivoted to the frame and swinging in vertical planes at the rear of the panel, said panel 110 being provided with a ledge for engagement with the arms, and actuating devices for the panel embracing means connected with and acting on the arms, substantially as described. 115

11. The combination with an organ casing 120 having a sliding top, of a sliding panel for closing the space at the front of the keys, said panel being constructed to overlap the front wall of the casing, guides for said panel consisting of vertical guide pins on the panel, 125 bearings for said guide pins attached to the front wall below the same, springs applied to depress the panel, and means actuated by the sliding top for lifting the same, substantially as described. 130

12. The combination with an organ casing, a sliding top located over and adapted to cover the keys and to form a desk top when drawn forward, a movable part or panel which serves

to close an opening in the organ casing and which is actuated by movement of the sliding top, and operative connections between the sliding top and said movable part or panel, comprising a lever pivoted to the back of the case and swinging in a horizontal plane beneath the sliding top, and a roller on the under surface of the sliding top, provided with a flange at its lower edge to sustain the free end of the lever, substantially as described.

13. The combination with an organ casing, a sliding top located over and adapted to cover the keys and to form a desk top when drawn forward, a movable part or panel which serves to close an opening in the organ casing and which is actuated by movement of the sliding top, and operative connections between the sliding top and said movable part or panel comprising a lever and a projection or roller on the sliding top engaging said lever to move the same; the front end or extremity of said lever being arranged at an angle to the main part thereof, whereby the lever is moved during a part only of the movement of the top, substantially as described.

14. The combination with an organ casing, a sliding top and a folding pedal support, of a lever pivoted to the rear part of the casing and swinging in a horizontal plane, a roller or projection on the sliding top engaging said lever, and operative connections between the said lever and the said folding pedal support, substantially as described.

15. The combination with an organ casing, a sliding top and a folding pedal support, of a lever pivoted to the rear part of the casing and swinging in a horizontal plane, a roller or projection on the sliding top engaging said lever, and operative connections between the said lever and the said folding pedal support, substantially as described.

16. The combination with an organ casing, a sliding top and a folding pedal support, of a lever pivoted to the rear part of the casing and swinging in a horizontal plane, a roller or projection on the sliding top engaging said lever, and operative connections between the said lever and the said folding pedal support, substantially as described.

which arms are connected respectively with 45 the said lever and with the folding support, substantially as described.

16. The combination with an organ casing, of a sliding top adapted to be drawn forward over the keys to form a desk top, and a locking device for holding the said sliding top in position when drawn forward, said locking device comprising bolts on the sliding top which engage recesses in the frame, and movable finger pieces located in recesses in the top and connected with said bolts, substantially as described.

17. The combination with an organ casing and a sliding top adapted to be drawn forward over the keys to form a desk top, a hood located above the level of the horizontal desk top, a casing within the hood, a movable screen for covering the front of said casing, and a support for the screen comprising a bar attached at its ends to arms which are pivoted to the sides of the casing, said bar being hinged to the screen, substantially as described.

18. The combination with an organ casing and a sliding top adapted to be drawn forward over the keys to form a desk top, a hood located above the level of the horizontal desk top, a casing within the hood, a movable screen for covering the front of said casing, a support for the screen comprising a bar attached at its ends to arms which are pivoted to the sides of the casing, said bar being hinged to the screen, and a sliding flexible curtain engaging the sides of the hood, and extending over said casing and screen, substantially as described.

In testimony that we claim the foregoing as our invention we affix our signatures in presence of two witnesses.
